UNITED STATES PATENT OFFICE.

JOHN ROHDIEK, OF BROOKLYN, NEW YORK.

SKATE.

Application filed January 16, 1926. Serial No. 81,635.

This invention relates to skates, and has for its object to provide an improved skate which when used will be very agreeable to the user and will enable the various shocks to which skates are subjected, to be readily absorbed by a mechanism provided in the skate so that such shocks are not transferred to the user of the skate. More particularly, the object of the invention is to provide a very simple structure which can be readily manufactured at a small expense and simplicity of manufacturing machinery.

For the fulfillment of these objects the invention consists essentially of a skate frame having shock absorbing chambers therein in which the shock absorbing mechanism is provided. These chambers are preferably made of one piece with the frame of the skate whereby a simple means is provided which can be readily manufactured.

The invention, in an embodiment thereof, will be described hereinafter, shown in the drawings, and finally pointed out in the claims.

In the accompanying drawings,

Figure 1 is a side view particularly in longitudinal section of my improved skate; Fig. 2 is a plan view of the frame of my improved skate;

Fig. 3 is a vertical transverse section taken on line 3—3 of Fig. 1; and Fig. 4 is a horizontal section taken on line 4—4 of Fig. 1.

Similar characters of reference indicate corresponding parts throughout the various views.

Referring to the drawings, and more particularly to Fig. 2, my improved frame consists essentially of two parts, a rearward part and a forward part. The rearward part indicated by portion 10 has a chambered portion 11, with a bottom of substantially circular shape, and this chambered portion extends at the rear of the rearward portion 10, upwardly to frame the counter of the skate frame and has a configuration substantially that of the counter of the shoe of the user. This counter portion 12 is made of one piece with the chambered portion 11, so that the entire rearward portion of the skate frame may be struck out by suitable manufacturing machinery, as one piece. The rearward portion 10 is provided with an opening 13 through which a bolt 14 passes, which has a nut 15 on the screw

threaded end of the bolt 14. This bolt 14 engages a slot 16 of the forward portion 17 of the skate frame, and by the operation of the nut 15 and the bolt 14 the forward portion 17 and rearward portion 10 may be adjusted in respect to each other, whereby the frame may be adapted to be used with shoes of different sizes. The rearmost portion of the rearward portion 10 is provided with suitable means as screws 18, which secure straps 19 thereto as shown in Fig. 1, and a suitable strap 20 is applied by any suitable means to the counter portion 12, in order to surround the ankle of the user. The rearward portion 10 is further provided with an opening 21 through which a nozzle portion 22 of a pneumatic shock absorbing device passes. This nozzle 22 is provided with a suitable valve of any well-known construction, indicated by 23. The pneumatic shock absorbing device consists essentially of a rubber sphere indicated by 24 and which has a configuration substantially that of the configuration of the chambered portion 11, whereby this spherical portion 24 is slotted within the chambered portion 11. The single pneumatic portion 24 is in the nature of a balloon. The chambered portion above the pneumatic shock absorber 24 remains free and open for the entrance therein of the heel of the shoe.

The forward portion of the frame is also provided with a chambered portion 30 partially of straight walls with a circular bottom 31. Within the chambered portion 30 at the upper part thereof, a solid block of rubber of circular shape indicated by 32 is provided, upon which the forward portion of the shoe rests.

This block of rubber 32 in turn, rests upon a metallic disk or plate 33 having at its central portion a cylindrical tubular member 34, in which seats a piston member 35 having a seat portion 36 resting upon the bottom 31 of the chambered portion 30. The tubular member 34 is provided with interior screw threads and the piston member 35 is provided with exterior screw threads. By the members 34 and 35 being adjusted in respect to each other the adjustment of the block of rubber 32 is brought about so as to have this block 32 in the proper position. The resiliency of the forward part of the shoe is obtained as a result of the resiliency of the block of rubber 32. The forward portion 17

is provided with depending members 37 and a screw bolt 38 adapted to be engaged by the usual key which operates in the well known side flanges 39, in order to grip the sole of the shoe to the forward part of the skate.

By the arrangement of the parts as has been described, the heel portion of a user is resiliently sustained in position by the shock absorbing device, so that this most sensitive part of the user is not subjected to the continual shocks which the roller skater is usually subjected to. The rubber resilient block 32 takes up the vibrations at the forward end of the foot of the user. This rubber resilient member 32 being arranged in proximity to the ball of the foot. Both the chambered portion 11 and the chambered portion 30 have also downwardly extending flanges 40 and 41 respectively, through which the shafts 42 of the wheels 43 pass.

Thus it will be seen that the portions of the skate with their chambered portions and the shaft journaled portions are of one piece, which can be readily struck out by machinery and made at a very low expense. They may be readily assembled and by the insertion of the shock absorbing device, a skate is provided which is resilient in use and agreeable to the user.

My improvements as I have described them are shown as applied to a roller skate, the wheels being suitably arranged in the well known manner to the shafts 45. But the structure as described may be readily applied to ice skates, by simply having the shafts pass through the ice blades and by a suitable lock device the said blades may be fastened to the shafts. The ice blades are inserted between the depending flanges 40 and 41, and suitable nuts are provided to hold the ice blades readily in position.

I have shown an embodiment of my invention but it is clear that changes may be made therein without departing from the spirit of the same as defined in the appended claims.

I claim as new:

1. A skate comprising a frame consisting of forward and rearward portions adjustably joined, said portions having chambered

parts therein, and a pneumatic shock absorbing device in one of said chambered parts.

2. A skate comprising a skate frame consisting of two parts, each part having a chambered portion, a pneumatic shock absorbing device in one chambered portion, and an adjustable cushion shock absorbing device in the other portion.

3. A skate comprising a skate frame consisting of two portions, each portion having a chambered portion, a shock absorbing device in each chambered portion, and means for joining said two portions adjustably together, a counter portion on one of said chambered portions integrally therewith, and a shaft supporting members integral with each chambered portion.

4. A skate comprising a skate frame formed of two parts, a rear part and a forward part, the said rear part having a chambered portion with a counter portion extending upwardly therefrom and a shaft supporting portion extending below the same, said chambered portion having a spherical pneumatic member therein with means for maintaining resiliency, said means extending through the chambered portion, and said rearward portion having also suitable straps, said forward portion having a chambered portion, an adjustable member in the chambered portion, a resilient rubber block on said adjustable portion, shaft supporting members on said chambered portion, and clamping means on said forward portion, and means joining the forward and rearward portions adjustably together.

5. A skate construction comprising a skate frame having chambered portions in its rear and forward portions, a pneumatic shock absorbing device in the chambered rear portion for receiving directly the heel of the wearer's shoe, and a shock absorbing device in the forward chamber directly exposed to the sole of the shoe and adjustable toward and from said shoe.

In testimony that I claim the foregoing as my invention, I have signed my name hereto.

JOHN ROHDIEK.
